UNITED STATES PATENT OFFICE.

LUCIEN A. MARSH, OF SAN FRANCISCO, CALIFORNIA.

GAS-STOVE AND BURNER LIGHTING DEVICE.

1,200,385.

Specification of Letters Patent.

Patented Oct. 3, 1916.

Application filed January 19, 1916. Serial No. 72,934.

To all whom it may concern:

Be it known that I, LUCIEN A. MARSH, a citizen of the United States, residing in the city and county of San Francisco and State of California, have invented new and useful Improvements in Gas-Stove and Burner Lighting Devices, of which the following is a specification.

My invention relates to improvements in devices for igniting gas at burners, such as are employed for gas stoves and plates and the like.

It consists in the novel combination including two parallel supply manifolds forming a single element, connections between one of these manifolds and the burners proper and connections between the other manifold and a pilot light, and cocks having passages therethrough so that in turning a cock gas will be admitted first from one of the manifolds to the pilot light and upon a further turning of the cock gas will pass from the other manifold to the burner, at which point the gas from the burner will meet the jet of ignited gas which is directed from the pilot head to each of the burners, thereby igniting the gas at the burner at the instant of its escape to prevent any waste or disagreeable smell from unignited gas which might otherwise escape at the burners.

The invention also comprises details of construction which will be more fully explained by reference to the accompanying drawings, in which—

Figure 1 is a plan view of four burners with their intermediate pilot burner manifold and controlling cocks. Fig. 2 is a transverse section of the manifolds and a connecting cock and passages. Fig. 3 is a similar view at right angles to Fig. 2. Fig. 4 is a transverse section of the plug. Fig. 5 is a section taken on the line 5—5 of Fig. 1. Fig. 6 is a modification of the manifold. Fig. 7 is a section of the pilot light. Fig. 8 is a modification of the same.

In my invention I have devised a simple arrangement by which the pilot light is independently supplied with a small constant jet of gas, and when any of the cocks to the main burners is opened, an additional supply of gas will be supplied, ignited and directed to the main burner head, so that at the instant when the gas is supplied to the main burner, it will be met by the flame

of the pilot light and ignited without any escape of gas at that point.

As shown in the drawings, the gas supply is received through a main or manifold A, which extends horizontally and adjacent to the burners to be supplied. Pipes 2 connect this main with burner heads 3, and these pipes have cocks 4 by which either of them may be opened to receive gas from the main A. In order to ignite any one or more of these burners a pilot light head is located substantially central between the main burners and approximately at the same level. This pilot light consists of a cylindrical case 5 having openings made through its side and directed to the main burners. Within this case is the pilot burner 6, having jets 7 directed horizontally and through the openings 8 of the outer case; these jets, as above described, being directed to the main burner heads. In order to supply this pilot light with a small, constant flame, the head is connected by a pipe 9 with the main A, and by means of a cock 10 an opening is made sufficiently to allow a small constant supply of gas to pass through the pipe 9 to the pilot light in the casing 5. This flame is small and constant, but when any of the burners is to be ignited it is done by turning a cock 4. This cock has a port which may be brought into line with the passage 11 leading through the pipe 2 to the burner. Below the contiguous jet main or manifold A, is a second main 12 which is closed at each end, but which has passages, as at 13, leading to the surface of the cock 4. A diagonally disposed, channeled port 14 is formed in the surface of this cock and when turned to a certain position it will connect the passage 11, and through this cock and port and the passage 13 will supply gas to the closed main 12. The gas passing through this main will thus reach a port 15 which independently connects with the pilot light through a pipe 16 which is concentric with the constant supply pipe 9. These connections will be made as follows: Upon turning the cock 10 a small jet will be supplied to the pilot head from the main A through the pipe 9. When the cock 4 is turned the diagonal surface port will be first brought into line with the passage 13 which connects with the closed main 12 and gas will immediately pass into this main and will thence flow through the passage 16 and

100
105
110

supply the jets in the pilot head which will be ignited from the flame already burning, and the supply will be so considerable that long jets of flame will be directed to the 5 burner head. Continuation of the turning of this cock will connect the main A directly with the passage 11 and conducting pipe 2 and with the burner head, which will thus be supplied with the proper amount of 10 gas and will be instantly ignited by the jet which proceeds from the pilot head, as above described. A further turning of the cock 4 will cut off the igniting supply from the closed main 12 and will reduce the pilot 15 light to its normal appearance, while the supply to the burner head may be increased or diminished by the further turning of the cock without any effect upon the reduced pilot light.

20 By the construction here described, it is possible to combine with the main gas conductor, a closed secondary chamber with a manually actuated means to transfer gas from the main through this chamber to the 25 pilot light head so as to temporarily increase the flame at this point, and to follow this by a supply of gas to the main burners, to be met and ignited by the pilot light flame, and to also regulate the main burner 30 flames independently of the pilot supply, with a minimum of pipes, cocks and connections.

Having thus described my invention, what I claim and desire to secure by Letters Patent is—

35 1. In a gas stove, a burner, a pilot light having a normally lighted jet and a second jet directed toward the burner, a two part gas manifold having a supply compartment 40 and a return compartment, a pipe leading from the supply compartment of the manifold to the first jet of the pilot light to furnish a constant supply of gas, a second pipe connecting the pilot light with the return 45 compartment of the manifold to furnish a supply of gas to the second jet, a connection between the burner and manifold supply compartment, and a cock arranged to open successively communication between the 50 manifold compartments and between the supply compartment and the burner.

2. The combination with a gas manifold, main gas burners, gas supply pipes connecting said burners to said manifold, and 55 valves in said gas supply pipes, of an igniting device comprising a pilot light having a jet designed to be constantly lighted

and a plurality of igniting jets directed toward the burners, a pipe constantly supplying the first jet of the pilot light with gas, 60 a conduit connected with the pilot light to supply the other jets with gas, a closed chamber connected with the burner pipes and with the conduit, and means whereby on operating each valve the gas will be directed into the closed chamber and successively with the respective burner.

3. In combination, a plurality of burners, a pilot light located between the main burners, a main supply manifold, direct connections and controlling cocks between said manifold and the burners, an independent connection and controlling valve to the pilot light, a chamber contiguous to the supply manifold, a connecting passage from said 75 chamber to the pilot light, and passages from the chamber to each burner supply cock, the plugs of said cocks having ports by which gas may be transferred from the manifold to the chamber and to the pilot 80 light.

4. The combination with fixed burners, and an intermediate pilot light casing, of a contiguous gas supply manifold and a closed chamber, pipes and controlling cocks 85 between the manifold and the burners, an independent pipe and cock between the manifold and the pilot light, a port from the closed chamber to the pilot light pipe, and ports from said chamber to the burner 90 controlling cocks, the plugs of said cocks having passages by which gas may be transferred from the manifold to the closed chamber and to the pilot light.

5. The combination with a gas manifold, 95 main gas burners, gas supply pipes connecting said burners to said manifold, and valves in said gas supply pipes, of an igniting device comprising a single chamber common to all the valves, the latter being provided with means for admitting gas from the manifold to the chamber prior to opening 100 communication between the manifold and the respective burners, a pilot light adapted to direct its flame toward the burners, and a pipe connection between the pilot light and the chamber.

In testimony whereof I have hereunto set my hand in the presence of two subscribing witnesses.

LUCIEN A. MARSH.
